UNITED STATES PATENT OFFICE.

ALBERT A. LONGAKER, OF CHAMBERSBURG, AND WYLLIS H. MARKLAND, OF ALTOONA, PENNSYLVANIA, ASSIGNORS TO CHAMBERSBURG ENGINEERING COMPANY, OF CHAMBERSBURG, PENNSYLVANIA, A CORPORATION OF PENNSYLVANIA.

SPRING-BENDING PRESS.

1,114,699.

Specification of Letters Patent.

Patented Oct. 20, 1914.

Application filed February 11, 1914. Serial No. 818,128.

To all whom it may concern:

Be it known that we, ALBERT A. LONGAKER and WYLLIS H. MARKLAND, citizens of the United States, the former a resident 5 of Chambersburg, in the county of Franklin, and the latter a resident of Altoona, in the county of Blair, both in the State of Pennsylvania, have invented certain new and useful Improvements in Spring-Bend-10 ing Presses, of which the following is a specification.

Our invention relates to improvements in presses for forming spring leaves from flat blanks, and more particularly for forming 15 heavy elliptical spring leaves such, for instance, as are used in locomotives and railway cars, and the objects of our invention are to cheapen and shorten the time of manufacture of such springs and to furnish 20 any number of spring leaves each of which will be an exact duplicate of the others.

Our press consists of a suitable housing having at the lower end a base and at the upper end a cap. About midway between 25 the cap and base is a fixed table and directly beneath this table is a punch table, suitably carried, and held against a certain amount of upward pressure by constant water pressure by the pistons of cylinders which are suitably carried, by the 30 fixed table for instance.

Guided by the housings at the sides of the machine is a vertically moving top table, actuated preferably by three hydraulic cylinders; although this may be modified to suit springs of different sizes, carried by the cap, and a bottom vertically 35 actuated table similarly actuated through cylinders carried in the base of machine.

40 The bottom movable table and the punch table carry dies and punches which are readily removable and adjustable for shearing or punching the ends of the blanks to the desired shape and also to give the blank 45 a preliminary bend near the ends, also a nibbing die and punch for nibbing the blank near its center and the top of the fixed table and the bottom of the movable table carry dies, easily removed and 50 changed, between which the blank operated upon by the lower dies and punches is completed. The nibbing punch is free to move vertically in the punch table, its vertical

movement being controlled by a stop or gage in the fixed table.

The blanks are first operated upon in the lower dies and are then, without reheating, moved to and finished in the upper dies. The set of three hydraulic cylinders for actuating each set of dies are entirely separate from each other and each cylinder of each set of cylinders may be separately operated so as to produce a low, an intermediate, or a high pressure tonnage as may be necessary for the work in hand.

In the accompanying drawings forming part of this specification and in which similar letters of reference indicate similar parts throughout the several views: Figure 1, is a front elevation of our spring leaf forming press; Fig. 2, an elevation of the right hand end of Fig. 1; Fig. 3, a section of Fig. 1 on line C—D; Fig. 4, a section of Fig. 1 on line A—B; Fig. 5, a plan of a spring leaf after having been completed in 75 the press; Fig. 6, plans of another form of spring leaf after having been operated upon in the press.

1 is a cap and 2 a base. The base carries three hydraulic cylinders each of which is 80 fitted with a plunger 7. The cap also carries one or more hydraulic cylinders each of which is fitted with a plunger 8. The cap and base are tied together by columns 14 which are shouldered at their tops and 85 bottoms and furnished with nuts 36 to hold the base and cap rigidly against the shoulders. Owing to the shoulders these columns serve not only as fixed distance pieces between the cap and base, but also take care 90 of the tension strains of the machine.

Guided upon columns 14 is an upper moving table 3, operated by plungers 8, and a lower moving table 4, operated by the plungers 7.

5 is a fixed table carried by columns 14 and located about midway between cap 1 and base 2. This table is supported by countersunk split collars 11 in the table 5 and secured by split nuts 10.

6 is a punch table vertically movable upon the columns 14.

13 are bolts, carried by fixed table 5, which limit the downward movement of table 6, and 12 plungers of hydraulic cylinders, also carried by table 5. The cylin-

ders of the plungers 12 are under a constant water pressure which is admitted to their cylinders through ports 26, Fig. 1.

It will be observed that there is a gap between the fixed table 5 and the punch table 6 to permit the latter to recede at the proper time.

The operation of the upper and lower moving tables 3 and 4 is controlled by a valve 20, Fig. 2, through front or back treadles 23—24 mounted upon cross shafts 21—22 and distributing valves 25, one for each water system of the upper cylinders the other for the lower cylinders. These valves are fully described in Letters Patent of the United States issued to W. H. Derbyshire on April 5, 1904, No. 756,595 and will not need to be described or illustrated in detail here. It will be sufficient to say that the arrangement of the valves is such that water may be admitted by them to pipes 30—31 which lead, the first, to the central one of the three upper cylinders, the second to the central one of the three lower cylinders, or through pipes 32—33, the first leading to the two upper end cylinders and the second to the two lower end cylinders in order that selective tonnage may be obtained for the operation of either the upper or lower moving tables. If the cylinders be of 25 tons capacity each water admitted to the central cylinder will cause it to exert a pressure of 25 tons on the table to which its piston is attached; if to the end cylinders and not to the central one there will be a working pressure of 50 tons, and if to all three cylinders a working pressure of 75 tons. The treadles 23—24 are for operating the valves which control the flow of water to the cylinders and after having been depressed for admitting a flow of water are, when released, returned to their first position by a spring 27.

19 is a pull-back cylinder operating under a constant hydraulic pressure for lifting the upper movable table after it has been lowered to bend the spring between the dies 17—18, the upper one of said dies being carried by this table and the lower one by fixed table 5. A pull-back cylinder may be used in connection with the lower hydraulic cylinders but ordinarily this will be unnecessary as the weight of the several parts will be sufficient to accomplish their return without other aid.

The operation of the press is as follows: For leaves similar to that shown Fig. 5, a straight leaf 35 which has been sheared to approximately the proper length is inserted in the lower part of the machine and rests upon the lower part of the dies 15 carried by movable table 4. Pressure of water is now admitted to one, two or three of the cylinders carrying plungers 7, as may be necessary for the work in hand, and the

table 4 lifts until the ends of the blank contact with the faces of forming dies 15 carried by punch table 6, and on account of the greater pressure exerted by cylinders 2 as compared to cylinders 26 the punch table 6 is lifted by the power transmitted through the dies 15. The punch 36 is firmly secured to table 5 and passes through the upper dies 15, and by the upward travel of the blank the necessary slot is punched in the same, afterward, by the upper travel of blank and dies, the punch table 6 is brought firmly in contact with fixed table 5 and forms end of blank to desired shapes. Or under certain conditions of lighter material this forming would be performed previous to the tables 5 and 6 coming in contact. When the pressure is released from cylinders 2, table 6 is forced downward by cylinders 26 and strips the blank from punches 36. For a blank of this nature the nibbing punch 16 makes the necessary nib in the blank when table 4 is in upper position.

For leaves as shown in Fig. 6, suitably shaped dies and punches 15—36 are employed. The operation, however, is modified in that the table 4 is raised twice. In the first operation only a part of the slot is cut away (see the upper figure of Fig. 6) and the gage or stop for the nibbing punch 16 is moved away so that the punch 16 is free to ascend without making an impression on the blank. After this operation is completed and table 4 has returned to rest, the blank is shifted and the gage for nibbing punch 16 moved to arrest vertical travel of punch 16 and on the second ascent of table 4 the remainder of slot is punched and the center nibbed as shown in the lower figure of Fig. 6. After completion of the operations in the lower press, the blank is transferred to upper press of the machine. The plungers 8, one, two or all three of them, depending upon the pressure desired, are now operated to lower the upper moving table 3 when the die 17 carried thereby engages the top of the leaf and bends it in the dies 17—18 to the proper camber. The operator now throws the valves to lower table 4 when the partly finished leaf is removed from dies 15 and is placed, without reheating, upon the lower die 18 in the upper press of the machine. The plungers 8, one, two or all three of them, depending upon the pressure desired, are now operated to lower the upper moving table 3 when the die 17 carried thereby engages the top of the leaf and bends it in the dies 17—18 to the proper camber.

In order that the upper table may not travel unnecessarily, the columns 14 are threaded and carry split nuts 9 which may be so adjusted as to limit the operative movement of the plungers carried in the constant pressure pull-back cylinder 19.

We consider the arrangement of the machine as shown in the drawings as probably the best: it will be understood, however, that it may be arranged to operate horizontally instead of vertically, and that the position of the top and bottom presses may be reversed if desired without departing from the spirit of our invention.

Having thus described our invention we claim as new and desire to secure by Letters Patent:—

1. A hydraulic press of the character set forth, comprising, in combination, a fixed cap and a fixed base, a housing connecting said cap and base, hydraulic cylinders carried by said cap and base, plungers carried by said cylinders, die carrying tables carried by said plungers adapted to be guided in their movements by the housing of the machine, and a fixed die carrying table, carried by said housing, between the tables carried by said plungers.

2. A hydraulic press of the character set forth, comprising, in combination, a fixed cap and a fixed base, hydraulic cylinders carried by said cap and base, plungers carried by said cylinders and operating toward the center of the press, movable die carrying tables secured to said plungers, means for guiding said tables in their movements, and a fixed die carrying table located approximately midway between said cap and base.

3. A hydraulic press of the character set forth and comprising, in combination, a fixed cap and a fixed base, columns forming distance pieces and guides securing said cap and base, hydraulic cylinders carried by said cap and base, plungers carried by said cylinders and operating toward the center of the press, a movable die carrying table secured to the upper set of plungers, a movable die carrying table secured to the lower set of plungers said tables being guided in their movements by the columns securing said base and cap, a fixed die carrying table

secured to said columns approximately midway between said cap and base, and dies carried by said table adapted to operate in connection with dies carried by the upper and lower movable tables.

50

4. In a hydraulic press of the character set forth, in combination, a base and a cap, a lower set of hydraulic rams carried by said base and an upper set of hydraulic rams carried by said cap, columns forming tension members and distance pieces for securing said cap and base, a substantially central fixed table carried by said columns, a movable table operated by said lower set of rams and a movable table operated by said upper set of rams, a die one member of which is carried by the table actuated by the upper set of rams and the lower member of which is carried by the fixed table, a punch table beneath said fixed table, hydraulic rams carried by said fixed table and operating under constant pressure against which said punch table abuts, die members carried by said lower movable table and said punch table, and means for controlling the admission and exhaust of liquid to said lower and upper set of rams.

5. In a hydraulic press as set forth, in combination, an upper stationary die member and means for carrying the same, a movable die member, a movable table for carrying said latter member, hydraulically operated means for actuating said table, threaded columns upon which said table is guided, and nuts carried by said columns for limiting the upward movement of said table.
